UNITED STATES PATENT OFFICE.

FRED G. SHOUDY, OF ROCKFORD, ILLINOIS.

DESIGN FOR A GROCER'S CABINET.

SPECIFICATION forming part of Design No. 22,731, dated August 22, 1893.

Application filed April 25, 1893. Serial No. 471,838. Term of patent 7 years.

To all whom it may concern:

Be it known that I, FRED G. SHOUDY, a citizen of the United States, residing at Rockford, in the county of Winnebago and State 5 of Illinois, have invented and produced a new and original Design for a Grocer's Cabinet, of which the following is a specification, reference being had to the accompanying drawing.

The cabinet is composed of ends 1, having 10 their rear edges straight, and their front edges inclined inward at the top, and provided with a cornice or molding 2, at the top, panels 6, upper and lower cross pieces 7, and an intermediate cross-piece 8 which latter cross-piece 15 has oppositely beveled edges, the front being divided by vertical and horizontal partitions

3, and doors 4. This cabinet is supported upon legs 5.

The leading features of the design are the inclined ends having straight rear edges, the 20 front divided by horizontal and vertical partitions, and upper and lower cross-pieces and the intermediate cross-piece having oppositely inclined edges.

What I claim is—

The design for a grocer's cabinet herein shown and described.

25 FRED G. SHOUDY.
